UNITED STATES PATENT OFFICE

ABRAHAM KIMBER, OF MUNCIE, INDIANA.

IMPROVEMENT IN CAR-COUPINGS.

Specification forming part of Letters Patent No. 147,651, dated February 17, 1874; application filed December 6, 1873.

To all whom it may concern:

Be it known that I, ABRAHAM KIMBER, of Muncie, in the county of Delaware and State of Indiana, have invented a new and valuable Improvement in Car-Couplings; and I do hereby declare that the following is a full, clear, and exact description of the construction and operation of the same, reference being had to the annexed drawings making a part of this specification, and to the letters and figures of reference marked thereon.

Figure 1 of the drawings is a representation of a side view of my car-coupler. Fig. 2 is a plan view of the same. Figs. 3 and 4 are sectional views of the same.

This invention has relation to railroad-car couplings of the self-coupling kind. It consists in a novel construction of knobs or hooked and recessed enlargements on the exposed ends of the draw-bars, in combination with spring-retainers and uncoupling-arms, as will be hereinafter explained.

The following is a description of my coupling:

In the annexed drawings, A A represent two draw-bars, which are coupled together by means of an oblong link, C, across the middle of the length of which is a tie-bar, C', for a purpose hereinafter explained. The buffers are constructed exactly alike in every respect; hence it will only be necessary for me to particularly describe one of them. B represents a knob or enlargement, which is formed on the upper side of the draw-bar A, at its front end, or that end which is exposed beyond the end of the car-platform. This enlargement B presents a laterally-rounded and backwardly-inclined upper surface, b, at the front termination of which is a semicircular horizontal recess, a', and notches a a. The rear end of the enlargement B is under-beveled, as shown at c, and laterally rounded, forming a kind of hook on said enlargement. S represents a bifurcated spring, which is arranged horizontally in rear of the enlargement B, so that its free ends nearly touch the under-beveled surface c. Beneath this forked spring is a space for receiving the end of the coupling-link, as shown in Figs. 1 and 3, in which position of the link it

lies upon an arm, L, which is fixed to a transverse rocking bar, l, having on one end a crank, l'.

By throwing up the arm L, which can be done from the platform of the car, by means of a chain connected to the arm l', the end of the link C will be raised to the top of the enlargement B, when this link can be drawn from beneath the spring S and detached from the draw-bar.

To adjust the link C for self-coupling, when the two cars come together, it is arranged as shown in Fig. 3, in which position the cross-bar C' is received in the notches a a, and the rear end of the link is held beneath the spring S. When the bar A with its link thus adjusted is brought suddenly against another bar, A, the link will be moved forward and out of the notches a, and a coupling will be effected.

E represents a recess for receiving the well-known link for making a coupling in the ordinary way, with a link and pin, the latter being inserted through a hole, e. The recess a', in the top of the enlarged portion B, is also intended for receiving an ordinary coupling-link.

Having described my invention, what I claim as new, and desire to secure by Letters Patent, is—

1. The draw-head A, having the enlargement B and a rear-beveled under surface, c, in combination with the retaining-springs S, to hold the links on its upper surface until draft is applied, substantially as specified.

2. The combination of the draw-head A, having the enlargement B, and the lifting-arm L and spring S, as described.

3. The draw-head A having enlargement B, in which are notches a a, in combination with the link having the cross-bar c and the spring S, substantially as specified.

In testimony that I claim the above I have hereunto subscribed my name in the presence of two witnesses.

ABRAHAM KIMBER.
